DESIGN FOR A LIGHTING-FIXTURE WALL BRACKET.

Application filed February 9, 1929. Serial No. 29,984. Term of patent 3½ years.

To all whom it may concern:

Be it known that I, JOSEPH NOVIN, of the city of New York, county of Bronx, and State of New York, have invented a new, original, and ornamental Design for a Lighting-Fixture Wall Bracket, of which the following is a specification, reference being had to the accompanying drawing, forming a part hereof.

In the drawing:

Figure 1 is a front elevational view of the lighting fixture wall bracket, the parts shown in full line outline being ornamented in the same manner as the parts more fully illustrated, and

Figure 2 is a diagrammatic edge view in outline.

A dominating feature of the design resides in the employment of columns A of marble or like appearing material which contrasts with the metal employed in the remainder of the article.

I claim:

The ornamental design for a lighting fixture wall bracket substantially as shown and described.

JOSEPH NOVIN.
